UNITED STATES PATENT OFFICE.

GEORGE C. BRAINARD, JASON A. FITCH, AND ERIC E. WOLTERS, OF YOUNGSTOWN, OHIO, ASSIGNORS TO THE GENERAL FIREPROOFING COMPANY, OF YOUNGSTOWN, OHIO, A CORPORATION OF OHIO.

FIREPROOF SAFE CONSTRUCTION.

Application filed January 21, 1924. Serial No. 637,630.

This invention relates to improvements in fire-proof safe construction, having chiefly in view effecting economies in time and cost of manufacture, as well as providing an improved structure having inherent strength and fire-resisting capacity, and generally responding to Fire Underwriters requirements.

To that end, the invention contemplates a reduction in the number of parts and operations employed in fabricating a safe structure, thereby permitting of a maximum production in a minimum amount of time, and also requiring the stocking of only a minimum number of parts; thus conserving space and obviating the handling of bulky and unwieldy partly assembled safe structures.

Another important object of the invention is to so construct the door part of the safe as to permit the contemporaneous drying thereof with the safe body, and in a manner that will assure the eliminating of all free water and moisture before the facing or finishing plates are fitted thereto thus eliminating the possible development of rust, as in some safe constructions heretofore made. Therefore, it is proposed by the present invention to construct the doors of the safe in such a manner that the drying period therefor is equivalent to the drying period for the body and back thereby making it possible to time the drying operations of the body and its back, and the doors, so that the same may be carried out contemporaneously thereby permitting each safe to be put through the drying oven as a complete unit.

A further object of the invention is to provide a simple and practical means for making the door frame and the back panel in such a way that these members are held together under tension by suitable ties, such as rods, which together constitute a cage for reinforcing the insulation shell. With this construction it is possible to tighten the back to the body or shell uniformly at all points, and at the same time permit the tension members to be embedded within the insulation shell in such a way as to afford maximum protection from heat. Also by reason of the manner in which the tension members are connected with the door frame and structural element of the back panel, there will be no tendency for the tension members or rods to push or pry the back panel away from its

seat on the insulation shell in event that sufficient heat should be conducted thereto to thereby cause their elongation. That feature is, in part, provided for during the molding and baking operations in the course of manufacture as will hereinafter more fully appear.

A further important object of the invention is to assemble and locate the built-up reinforcing cage of the body in such a way, that expanded metal or like reinforcement may be anchored or attached thereto so as to definitely locate such reinforcement and produce known reinforcing results in the insulation body.

A still further object of the invention is to provide an improved door construction which utilizes a rectangular frame open at both sides so as to receive the insulation material, and thereby leave relatively large areas at both sides of the door exposed for drying purposes. In that connection the invention contemplates the use of removable front and back plates for the door which may be put in position after the insulation has been molded and coated with a surface of water-proof paint, the latter being employed to prevent absorption of atmospheric moisture by the insulation, thereby eliminating the possibility of rust at the inside of the metallic portions of the door.

With the above and other objects in view which will more readily appear as the nature of the invention is better understood, the same consists in the novel construction, combination and arrangement of parts herein-after more fully described, illustrated and claimed.

A preferred and practical embodiment of the invention is shown in the accompanying drawings, in which:—

Figure 1 is a perspective view of a safe constructed in accordance with the present invention.

Fig. 2 is a detail view of the primary structural element of the door frame.

Fig. 3 is a horizontal sectional view taken on the line 3—3 of Figure 1.

Fig. 4 is a vertical sectional view taken on the line 4—4 of Figure 1.

Fig. 5 is an enlarged detail horizontal sectional view showing more clearly the manner of placing the tension rods and their con-

nection with the door frame and back panel.

Figure 6 is a perspective view of the fac-
ing sheet for the door.

Fig. 7 is a more or less diagrammatic view
5 illustrating the manner in which the door
frames may be stacked during fabrication.

Fig. 8 is a detail view illustrating the
manner in which the tension rods constitut-
10 ing the skeleton cage for the body may be
fitted to the door frame.

Fig. 9 is a detail view illustrating the
manner of assembling a safe door.

Similar reference characters designate
15 corresponding parts throughout the several
figures of the drawings.

With a view to simplifying and expedit-
ing the manufacture of safes of the type
previously referred to, and yet combining
20 all of the structural features and advan-
tages of a safe of that type with the addi-
tional advantages obtained from the pres-
ent invention, it is desirable to make the
25 reinforcing cage of the body in such a way
that it is not necessary for the same to be
carried by the door frame during the pre-
liminary stages of manufacture.

That is to say, the door frame A must be
subjected to certain finishing operations
30 prior to the pouring of the insulation mate-
rial to form the insulation shell, and there-
fore in order to avoid the necessity of han-
dling a bulky construction consisting of
35 the door frame A and the skeleton cage B,
which not only occupies considerable floor
space as well as space within the ovens, it is
proposed to make the skeleton cage B in such
a way that it may be built up from a plu-
40 rality of tension members, ties; or rods 1,
or their equivalent, which may be readily
interlocked with the door frame A after
the door frames have been finished and set
45 up as the bottom of the mold for the body.
When the door frame A and skeleton cage
50 B consisting of the interlocked tension rods
1 and other reinforcements have been as-
sembled within the mold, and other rein-
forcement located as shown the insulation
55 shell may be poured to form the safe body,
and the pre-formed back section C may then
be placed upon the body and secured thereto
by the tension rods in such a way as to evenly
and uniformly clamp the back panel in
60 place.

As will later appear the doors D of the
65 safe, are made in a novel manner to facili-
tate handling and drying so that they may
be made contemporaneously with the body
of the safe instead of requiring a longer
60 period of drying as heretofore, thus obviat-
ing the necessity of holding-up the comple-
tion of a number of safe bodies due to the
delay in completing the doors.

The door frame A is constructed to in-
clude a primary structural element E which
65 is provided with a countersunk channel F

whose bottom wall is formed with the key
hole slots 2 or their equivalents, for receiv-
ing the heads 3 of the tension rods. Also,
as shown in Figure 2 the bottom of the
channel F may be provided with the open-
70 ings 2^a for permitting the cementitious in-
sulation material to flow into the door frame
when the same is used as the bottom of the
mold.

By reason of the fact that the tension rods 75
1 are detachably interlocked with the struc-
tural element E it is possible to make the
door frames A in any desired quantity, and
stack them as indicated in Figure 7. In
that way they occupy little space on the floor 80
while waiting their turn for embodiment in
a finished safe, while on the other hand they
may be easily manipulated and later placed
on the trucks for passage through the baking
ovens which dry or bake the paint. 85

It will therefore be apparent that by
reason of the fact that the door frames do
not have to initially carry the cage B which
is formed by the tension rods 1, considerable
labor is saved in handling while at the same 90
time the number of parts constituting the
cage is greatly reduced. Also this arrange-
ment does away with a multiplicity of weld-
ed joints usually occurring in a safe con-
struction of this kind. 95

After the door frames A have been made
in accordance with the predetermined speci-
fications, they are laid in the position shown
in Figure 8 and the mold members M and M'
are assembled as shown therein. The tension 100
rods 1 may be interlocked with the structural
member E by fitting the heads 3 of the ten-
sion rods in the key-hole slots 2 with the
threaded ends 4 of the rods projecting above
the plane of the seat which is to be formed 105
in the insulation body to receive the back
panel C. When the rods are thus assembled
a reticulated reinforcing fabric such as ex-
panded metal R or other wire mesh may be
interwoven with or attached to the rods 110
and thus be definitely located. The cementi-
tious insulation body or shell G may then
be poured to form the body, and this con-
struction, after setting, is placed in an oven
and subjected to a drying heat for the re- 115

The effect of such baking is to heat up the
cementitious material G as well as the ten-
sion rods 1, and by reason of the expansion
of the rods 1 their diameter will be increased 120
while in the oven. That is to say, the insula-
tion is poured about the rods and is in close
contact with the rods. The insulation is set
and dried in that position, but owing to
small differences of expansion and contrac- 125
tion due to varying temperatures there may
be a little looseness. There also may be
expansion of the rods in excess of the ex-
pansion of the insulation, producing a bind-
ing effect, or there may be an expansion in 130

heating in excess of rod expansion causing a small amount of loosening. Therefore, when the completed body is removed from the oven and allowed to cool the rods 1 will contract thereby leaving a well defined channel or space 5 entirely about the rods in such a way that there is no adhesion between the rod and the insulation body or shell G. That feature insures freedom of expansion 10 or elongation of the rod in event that the same is subjected to heat by conduction during a fire and permits the movement of the rod to go on freely and unhindered without damage.

15 In connection with the formation of the skeleton cage B by the tension rods 1 another distinctive feature of the invention exists, namely that of providing an anchoring means for expanded metal or other suitable mesh reinforcement R. As shown in Figure 20 5 such reinforcement may be placed around and about both the inside and outside of the rods 1 where it may be held by suitable clips or other ties. The positioning of such 25 reinforcement not only strengthens the insulation shell, but permits of locating the inner sheet of such reinforcement in such a way as to include one of the ribs which constitute a portion of the seat for the back 30 panel.

The back panel C includes in its organization a structural element C' of the same general type as the element E, except that instead of key-slots, the said member C' is 35 provided with openings 6 for receiving the threaded ends 4 of the tension rods so that the said rods may receive the clamping nuts 7 within the countersunk or depressed channel portion of the said member C'. Also 40 the insulation of the back provides definite clearance in insulation for the tension rods.

As will be observed from Figures 3, 4 and 5 the structural element C' of the back panel may be equipped with suitable clips 8 or 45 their equivalent for permitting the expanded metal R' for the back panel to be conveniently anchored in place. In connection with said reinforcement it may be observed that the same may be used in two layers having the mesh thereof running criss-cross while one of the pieces of expanded metal 50 may be turned into one of the dovetail ribs on the back panel.

During the pouring of the shell G and the 55 making of the back panel C, the same will be formed with the complementary tongue and groove members 9 and 10 which form a seat S for the back panel. This seat is adapted to receive a suitable plastic adhesive 60 or fire-proof cement so that when the back panel C is laid on the seat, and clamped to the shell by the tension rods and nuts, the adhesive material is uniformly forced throughout the joint, thereby firmly uniting 65 the back and the shell and sealing the joint in a fire-proof manner. It is apparent that the provision of the tension bolts and nuts makes it possible to uniformly distribute the clamping pressure between the back and the shell over the entire area of the back and the body, thereby insuring maximum rigidity and effecting the locking of the back to the primary structural element E of the door frame A in a simple, practical and expeditious manner. Also, by reason of the fact 70 that tension rods and other reinforcement 1 are encased and adequately housed and protected by the insulation, they are protected to a maximum extent from the absorption of heat by conduction. However, if under the 75 intensity of a fire the rods 1 should elongate it will be apparent from Figure 5 that such elongation may readily take place due to the fact that the rods are free from the insulation and expansion longitudinally will simply lift the nut 7 from its position on the bottom of the channel and structural member C' without in any way imposing a prying off or pushing strain on the back panel.

The insulation body B is, as previously indicated, surrounded by the metallic shell G which includes the side plates G' interlocking at their forward edges with a part of the door frame and engaged at their rear edges by the plate G² of the back section. The in- 80 side of the shell is formed by the inner side wall plates G³, the back wall plate G⁴, and the top and bottom plates G⁵ and G⁶, all of which are interlocked in such a way as to provide tight joints at the corners and seams. 85

Referring to Figure 9 which illustrates one of the doors D it will be observed that it is proposed to construct the same in accordance with the present invention in such a way that only the side frames 11 are made 90 prior to the operation of pouring the insulation material within the same as a part of the mold. As shown in Figures 3 and 9 the doors are provided with the stiffening members 12 which may be perforated as indicated at 13 and are attached to the hinge portion H of the side frames 11 as indicated at 14, a spacing washer 15 being employed to separate the attaching edge of the stiffening member from the inner face of the hinge 95 molding.

As will be observed from Figure 9 the door frame 11 is left open at both sides prior to pouring the insulation material, and that feature permits of adequately painting all 100 of the inner surfaces of the door molding. When the door frame is ready to receive a plastic composition the same is laid on a mold or its equivalent 16 and suitable mesh-reinforcement 17 placed therein, and the in- 105 sulating material 18 poured. After the poured insulation has received its initial set and is ready for the oven, it will be apparent that a relatively extended drying area for the door is provided. In other words the ex- 110 115 120 125 130

posed drying area or surface of the cementitious material 18 is greatly enlarged in proportion to the volume of such material, thereby making it possible to complete the 5 drying of a door of this type in from eight to eighteen days, whereas a door having only one side exposed for drying heretofore required from eighteen to twenty-four days for drying.

10 After the door has been oven-dried the surfaces 20 thereof may be provided with a coating of water-proof paint P, such paint forming a moisture proof envelope which prevents absorption of water from atmospheric air.

15 When the door has thus been dried and painted it is ready to receive the front or facing sheet 21 shown in Figure 6 and the back sheet 22. The said front sheet has its 20 side edges 23 and front edge 24 provided with suitable anchoring flanges whereby it may be slid toward the hinge edge H of the door while the back edge of said facing sheet 21 is provided with an offset portion 25 and 25 slots 26 whereby said offset portion may fit beneath the hinge molding of the door, and also straddle the washers 15. The back sheet 22 may be provided with the flange 26^a for engaging with the anchor member 27 as 30 shown in Figure 5 while the top and bottom edges thereof may respectively be provided with the locking flanges 28 as shown in Figure 4.

From the foregoing it will be apparent 35 that one of the novel and distinctive features of the present invention is the manner in which the tension rods 1 constituting the cage B are attached to the primary structural element E of the door frame after the 40 latter has been finished and set up as a part of the mold. That feature eliminates the necessity of carrying a large unwieldy body frame through the shop with the consequent elimination of much labor and care in 45 handling, while at the same time permitting the expanded metal lath reinforcement to be definitely attached to the tension rods by looping and twisting a piece of wire about the lath and wire to hold the lath in place 50 if desired to produce predetermined results so far as strengthening the insulating shell is concerned.

Another outstanding feature of the improvement resides in the manner of fabricating the door so as to make the time schedule of its completion substantially equal to that of the body, while at the same time the use of removable or separate back panels permits finishing after the insulation is dried 55 instead of before and insures uniform painting as to color while at the same time eliminating considerable re-handling and finishing.

60 We claim:—

65 1. A fire-proof safe construction including

an insulating monolithic body open at the front and rear, a door frame fitting the body at its front side, a separate back panel of insulating material and including a fastening anchoring element embedded therein, 70 said back panel being fitted to the rear side of the body, and rods engaging the door frame and fastening anchoring element of the back panel to draw the same together.

2. A fire-proof safe construction including 75 a hollow monolithic body of insulating material and a back panel also of insulating material fitted to one side of the body, anchoring elements of channel cross-section associated respectively with the doorway of 80 the hollow monolithic body and also with the back panel and having the bottoms thereof countersunk, and clamping rods for carrying means for engaging the countersunk bottoms of the fastening anchoring elements 85 to hold the back panel and body together.

3. A fire-proof safe construction including 90 a hollow monolithic body of insulating material and a back panel also of insulating material fitted to one side of the body, fastening anchoring elements associated with the doorway of the hollow monolithic body, and also with the back panel, said elements having countersunk portions, and fastening members extending through the walls of the 95 hollow monolithic body and having abutments at their ends bearing in the countersunk portions of the fastening anchoring elements whereby expansion of said fastening members will not force the back panel 100 from contact with the body.

4. A fire-proof safe construction including 105 a hollow monolithic body having a back panel receiving seat at one end, a fastening anchoring element at its front end, an insulating back panel adapted to fit into said seat, an adhesive cement for uniting the back panel with the body at the said seat, a fastening anchoring element carried by the back panel, tie means extending through the side 110 walls of the hollow monolithic body and engaging with the fastening anchoring element of the back panel and the fastening anchoring element of the body to unite the panel and the body under tension.

115 5. A fire-proof safe construction including a hollow monolithic body having a back panel receiving seat, an insulating back panel adapted to fit in said seat, an adhesive cement for securing and sealing the joint 120 between the back panel and the body at said seat, a fastening member projecting from said seat and piercing the back panel whereby the back panel and body may be locked together in addition to the holding back of 125 said cement.

6. A fire-proof safe construction including 130 a hollow monolithic body of insulating material and a back panel also of insulating material fitted to one side of the body, fas-

- tening anchoring elements associated with the doorway of the hollow monolithic body and also with the back panel, the said fastening element associated with the doorway 6 having a plurality of key-hole slots therein, headed fastening rods fitting in said key-hole slots and also passing through said hollow monolithic body and the fastening anchoring element carried by the back panel, 10 and means on the end of said rod projecting through the fastening anchoring element of the back panel for engaging with said element to clamp the panel and body together under tension.
- 15 7. In a safe door, an interior insulation slab, a door frame surrounding said slab, and front and back sheets for the slabs having means for providing an expansion joint with the door frame.
8. A safe door including an interior body 20 of insulation material, metallic moldings constituting the sides of the door frame, a back sheet interlocked with the moldings, and a front sheet interlocked with the front portions of the moldings and having an expansion joint connection with the edge of one of said moldings.
9. In a safe door, an insulation cast within an outer frame, said frame having rigid attachment to front and rear sheets perpendicularly to the plane of the sheets, and slipping attachment to the sheets in the plane 30 of the sheets.

In testimony whereof we hereunto affix our signatures.

GEORGE C. BRAINARD.
JASON A. FITCH.
ERIC E. WOLTERS.
